(57) **CLAIM**

The ornamental design for touch monitor, as shown and described.

DESCRIPTION

FIG. 1 is a front perspective view of a touch monitor according to a first embodiment of the present invention;

FIG. 2 is a front view thereof;

FIG. 3 is a top view thereof;

FIG. 4 is a rear view thereof;

FIG. 5 is a rear perspective view thereof;

FIG. 6 is a right side view thereof;

FIG. 7 is a left view thereof;

FIG. 8 is a right side view thereof, with the monitor swiveled in a forward tilted position;

FIG. 9 is a right side view thereof, with the monitor portion swiveled in a backward tilted position;

FIG. 10 is a front perspective view of a touch monitor according to a second embodiment of the present invention;

FIG. 11 is a front view thereof;

FIG. 12 is a top view thereof;

FIG. 13 is a rear view thereof;

FIG. 14 is a rear perspective view thereof;

FIG. 15 is a right side view thereof;

FIG. 16 is a left view thereof;

FIG. 17 is a right side view thereof, with the monitor swiveled in a forward tilted position; and,

FIG. 18 is a right side view thereof, with the monitor portion swiveled in a backward tilted position.

Broken lines shown in the drawings illustrate portions of the touch monitor, and form no part of the claimed design.
